SWITCH ASSEMBLAGE

William C. Furnas, West Allis, and Sigurd R. Thompson, Milwaukee, Wis.; said Thompson assignor to said Furnas, doing business under the name and style of Furnas Electric Company

Application July 12, 1937, Serial No. 153,152

3 Claims. (Cl. 200—168)

The present invention relates in general to improvements in the art of manufacturing electrical control mechanisms, and relates more specifically to improvements in the construction and 5 operation of switch assemblages and to housings for enclosing such assemblages.

Generally defined, an object of our invention is to provide an improved switch assemblage which is simple and compact in construction, 10 and which is also highly efficient and well protected when in use.

It is frequently desirable when utilizing electrical control mechanisms in moist and mussy places such as garages and filling stations, to 15 have these devices well protected by water-proof housings, while at the same time permitting convenient access to the mechanisms for inspection purposes. It is also desirable to have these mechanisms or assemblages durably constructed 20 so as to require minimum attention and to effectively resist excessive wear due to frequent operation. In order to minimize the cost of production of such devices it is moreover desirable to be able to construct the parts from sheet material 25 with the aid of punches and dies, and the parts thus produced should be formed for ready assemblage into the completed structures. None of the prior switch mechanisms heretofore provided especially for automobile hoist control 30 service, have met all of these requirements and could not therefore effectively withstand the severe service and abuse to which they were subjected.

Our present invention therefore more specifically contemplates the provision of improved 35 switch mechanism which effectively meets all of the above mentioned requirements, and which is highly efficient in operation.

A more specific object of our invention is to 40 provide improved moisture and dust proof housing structure for electrical devices such as switches, which will however permit most convenient access to the normally concealed mechanisms.

Another specific object of the invention is the 45 provision of an improved switch spindle and movable contact assemblage which is durable in construction and which may be readily manufactured and assembled.

A further specific object of our invention is the 50 provision of an improved support for the normally fixed contacts of a switch assemblage, and a new mode of mounting such supports in the frame structure of the switch.

An additional specific object of our invention

is to provide a new and useful controller for electrical apparatus, which may be manufactured and sold at moderate cost and which is extremely durable and presents a neat appearance.

The above and other specific objects of our invention will be apparent from the following detailed description.

A clear conception of embodiments of the several features constituting the present improvement, and of the mode of constructing and of operating switch assemblages built in accordance with our invention, may be had by referring to the drawings accompanying and forming a part of this specification wherein like reference characters designate the same or similar parts in the various views.

Fig. 1 is a central longitudinal vertical section through one of our improved switch assemblages with the closure cover in place and showing the switch in normal open position; 20

Fig. 2 is a partially dismantled end view of the switch assemblage, showing the enclosing cover released and partially removed from the switch frame;

Fig. 3 is a transverse vertical section through the switch assemblage, taken along the line 3—3 of Fig. 1 and showing the switch mechanism in open position;

Fig. 4 is a fragmentary transverse vertical section similar to that of Fig. 3 but showing the switch mechanism in closed position;

Fig. 5 is a fragmentary longitudinal horizontal section through the switch assemblage showing one of the fixed contact supports in the act of initial assembly thereof;

Fig. 6 is a similar sectional view showing a subsequent step in the assembly of the fixed contact support; and

Fig. 7 is a complete longitudinal horizontal section through the switch assemblage taken along the line 7—7 of Fig. 1, and showing the fixed contact supports fully assembled.

While our invention has been shown herein as having been embodied in a particular type of switch mechanism especially adapted to control automobile lifts, it is not our intent to thereby unnecessarily restrict the scope; and while certain sections have been referred to as having been taken along vertical and horizontal lines, 50 it will be obvious that the switch assemblage may be disposed in any desired position other than as shown.

Referring to the drawings, the improved switch assemblage comprises in general a frame hav- 55

ing a base composed of upper and lower base plates 9, 10, respectively, the upper of which is provided with integral upwardly projecting end walls 11, 12, and the lower of which has integral upwardly extending side flanges 13 spaced from the opposite side edges of the end walls; a pair of laterally spaced fixed contact bars or supports 14, 15 mounted in the end walls 11, 12 and carrying the fixed contacts 16; an oscillatory movable contact carrying spindle 17 journalled in the end walls 11, 12 between the fixed contacts 16 and providing a support for a series of movable contacts 18, 19 which are cooperable with the fixed contacts 16; and a removable U-shaped cover 20 formed for cooperation with the end walls 11, 12 and with the flanges 13 to completely enclose the switch mechanism.

The upper base plate 9 and the end walls 11, 12 may be formed of a single piece of sheet metal, 20 and the walls 11, 12 may be retained in substantially parallel position by means of a top bar 21 rigidly connecting the upper ends thereof. The upper and lower base plates 9, 10 may be firmly united by spot welding or otherwise; and the end 25 walls 11, 12 are provided with aligned rectangular slots or openings 22, 23 respectively, all of which are of the same height, but of which the openings 22 are somewhat wider than the openings 23. The end wall 11 is also provided with openings 24 for the electrical conductors and with a journal opening for the reduced end of the spindle 17; and both of the end walls 11, 12 are reenforced by outer plates 25 attached thereto by bolts or screws 26. The spindle 17 is directly journalled 30 in the end walls 11, 12 and plates 25, and these plates are somewhat larger than the end walls 11, 12.

The lower contact bars or supports 14, 15 are formed of insulating material and are adapted 40 to be mounted in the end walls 11, 12 of the main frame in the manner shown in Figs. 5, 6, and 7. Each of these bars or supports 14, 15 may have uniform rectangular cross-sectional area substantially equal to that of the openings 23 in the 45 end wall 12 but of slightly less width than the openings 22 in the opposite end wall 11. The contacts 16 are suspended from the bar supports 14, 15 by resilient conductor arms 27 secured in place by terminal bolts 28 some of which may be joined 50 by a conductor plate 29, and to which the electrical conductors may be attached by means of nuts 30. After the fixed contacts have been attached to the supports 14, 15, the latter may be assembled in the frame walls 11, 12 by first inserting one end of each support 14, 15 through 55 one of the larger openings 22 and by pushing or sliding the support through this opening sufficiently to permit swinging thereof into alignment with the corresponding opposite opening 23, as 60 clearly indicated in Fig. 5. The aligned end of the support 14, 15 may then be driven into the adjacent opening 23 as shown in Fig. 6, until it engages the outer plate 25, whereupon the opposite end of the bar will be flush with the outer surface 65 of the end wall 11. After both of the contact supports 14, 15 have been thus positioned in the openings 23, a retainer plate 31 may be applied to the end wall 11 and within the openings 22 in the manner illustrated in Fig. 7, so as to 70 finally lock the adjacent ends of both supports 14, 15 within the openings 22. When thus finally assembled, the supports 14, 15 will be disposed substantially parallel to each other and will be rigidly confined within the openings 22, 23 of both end 75 walls 11, 12, and the reenforcing and sealing plate

25 may be finally applied to the end wall 11 as shown.

The lower base plate 10 may also be formed of sheet metal with the aid of punches and dies, and the flanges 13 thereof may be inclined outwardly as shown in Figs. 2 and 3 so as to facilitate application of the cover 20. The flanges 13 are spaced from the adjacent sides of the upper base plate 9 so as to form elongated recesses within which pliable sealing strips 32 formed of sponge rubber or the like, are confined. The base plates 9, 10 may be provided with bolt holes 33 for effecting attachment of the main frame to a suitable support, and the surface of the plate 9 adjacent to the fixed contact supports 14, 15 may be covered with a sheet 34 of asbestos or the like. The end wall stiffening bar 21 may also be covered with asbestos sheeting if so desired, and it will be observed that the frame assembly although being formed of sheet metal throughout, is extremely rigid and durable in construction.

The movable contact carrier spindle 17 which is oscillatably journalled in the end wall 11 and in the reenforcing plate 25 of the opposite end wall 12, is formed of a bar of square or other polygonal sectioned stock 35, the medial portion of which is snugly embraced by a relatively long polygonal section bushing 36 formed of insulating material such as "bakelite". The end of the spindle 17 which coacts with the end wall 11 is turned to reduced cylindrical shape, and the opposite square end of this spindle is embraced by a bushing 37 having a circular bore as shown in Fig. 1. This bushing 37 is secured to spindle 17 by brazing 38, and is embraced by collars or bushings 39, 39' and a cap 40, the latter being rigidly but detachably secured to the bushing 37 and spindle 17 by means of a set screw 41 and having a manipulating handle 42 attached thereto. In the particular type of switch shown, the handle 42 is adapted to be automatically returned to switch open position when the actuating pressure is released, by means of a coil spring 43 embracing the bushing 39 and having one end cooperable with a lug 44 secured to the end wall 12 while its opposite end reacts against a crank plate 45 embracing the square "bakelite" bushing 36 and coacting with the end of the bushing 37, 39. With such assemblage, the spring 43 will be tensioned when the switch is closed, and this tensioning of the spring will cause the handle 42 and the movable contacts 18, 19 to be returned to open position when the handle is released. The contacts 18, 19 have square holes snugly embracing the inner insulating bushing 36, and are properly positioned and spaced apart by means of outer bushings 46 which are also formed of insulating material and snugly embrace the single inner bushing 36. The end of the stock 35 remote from the bushing 37, is screw threaded for the reception of a clamping nut 47 which clamps the contacts 18, 19 between the bushings 46 and the crank plate 45 against the bearing bushing 39.

The enclosing cover 20 may also be formed of sheet metal with the aid of punches and dies, and is of U-shape so as to permit disposition thereof over the tops of the side walls 11, 12 and in snug engagement with the inner surfaces of the outer plates 25. The opposite side portions 48 of the cover 20, are resiliently biased outwardly as shown in Fig. 2, so that the extreme edges thereof must be sprung in position between the side flanges 13 of the lower base plate 10 when the cover is assembled as illustrated in Fig. 3.

The inner portions of the ends of the cover 20 at the end walls 11, 12, are provided with pliable U-shaped sealing strips 49 formed of sponge rubber or the like, and the cover is adapted to be 5 detachably clamped into sealing position by means of screws 50 coacting with the cover 20 and with the top bar 21 as clearly shown in Figs. 1 and 3. The interior of the cover 20 between the sealing strips 49 may be lined with asbestos sheeting 51 or the like; and when the cover is finally applied to the frame assemblage, the sealing strips 49 are compressed against the edges of the end walls 11, 12 and the side portions 48 are forced against the sealing strips 32 so as to provide 10 a dust and water-proof enclosure for the switch mechanism.

When the improved switch assemblage has been properly constructed as above described and connected into the electric circuit, the movable contacts 18, 19 may be readily swung into engagement with the corresponding normally fixed contacts 16, by merely swinging the handle 42 so as to rotate the spindle 17. During such movement of the handle 42, the spring 43 will be placed under tension so that upon release of the handle 42, it will quickly return to vertical position and will disengage the contacts 18, 19 from the fixed contacts 16. During oscillation of the movable contacts 18, 19 into position between the normally fixed contacts 16, the resilient arms 27 will spread apart as shown in Fig. 4, thereby insuring tight closing of the switch.

As previously indicated, the switch assemblage may be mounted on a suitable support by the application of bolts to the openings 33, and these bolts should be provided with sealing washers so as to insure tight closing of the openings 33. The cover 20 may obviously be readily removed from the frame structure by merely releasing the 35 clamping screws, and thereafter withdrawing the cover, and when the cover is thus removed, the side portions 48 thereof will spring outwardly as shown in Fig. 2. Removal of the cover 20 obviously permits free access to all portions of the 40 switch mechanism. When the cover 20 is reapplied to the frame, the side portions 48 of the cover must be sprung into the position between the side flanges 13 of the base plate 10, and subsequent application of the screws 50 will force 45 the pliable sealing strips 49 into firm engagement with the end walls 11, 12, and will simultaneously force the extreme lower edge portions of the cover 20 into snug engagement with the flanges 13 and with the sealing strips 32. It has been 50 found that when the switch mechanism is thus concealed by proper application of the cover 20, a water-tight housing is provided and access of moisture to the contacts is absolutely prevented.

By virtue of the fact that the major portions 55 of the assemblage are all adapted to be formed of sheet metal with the aid of punches and dies, the assemblage may obviously be constructed and sold at moderate cost. The improved method of inserting the fixed contact supports 14, 15 in the manner shown in Figs. 5, 6, and 7, obviously facilitates assembly and produces a durable final structure wherein the fixed contacts are firmly supported. The single retainer plate 31 finally 60 confines both of the supports 14, 15 in proper position relative to the end walls 11, 12, and this plate 31 may obviously be quickly applied, or removed if necessary. The improved construction of the spindle 17 which carries the movable contacts 18, 19, is also of importance since it provides a spindle structure which can be manufac-

tured from standard stock and with minimum machining. The square stock 35 effectively supports the bushings 36, 46 of the movable contacts 18, 19, and prevents possible rotation thereof relative to the spindle. The formation of the bushings 37, 39 and of the cap 40, and the assemblage of these elements as shown and described, provides a durable manipulating connection between the handle 42 and the spindle 17. As previously indicated, the use of the spring 43 for automatically returning the spindle 17 to switch open position, is not essential, since some of these switches are formed so that when the switch is closed, it will remain closed until opened. This particular automatic return therefore is not an important feature of the present invention, although the bushings 46 and the clamping nut 47 provide simple and efficient means for clamping the crank plate 45 in position as well as functioning to space the contacts 18, 19 and to clamp these in position. The entire assemblage has proven highly successful in actual commercial use, and besides being readily manipulable and readily accessible for inspection, this assemblage may be manufactured at minimum cost and is extremely durable in construction.

It should be understood that it is not desired to limit this invention to the exact details of construction or to the precise mode of operation herein shown and described, for various modifications within the scope of the claims may occur to persons skilled in the art.

We claim:—

1. A housing for switch mechanism or the like, comprising, a frame having a base and side flanges and end walls formed integral with the base, said flanges and walls all extending in the same direction away from said base and the latter being disposed between the former, mechanism associated with said frame between said flanges and walls, a cover applicable to said frame over the edges of said end walls and having resilient opposite side portions biased outwardly for snug coaction with the internal surfaces of said flanges, a sealing strip secured within each end of said cover and being compressible against the entire edge of the adjacent end wall when said cover is applied to said frame, and a sealing strip secured to said base in contact with the inner side of each of said flanges, all of said strips being inter-engageable to provide an uninterrupted seal and said cover side portions being formed to compress said base supported sealing strips when said cover is applied to said frame to enclose said mechanism.

2. A housing for switch mechanism or the like, comprising, a frame having a base and side flanges and end walls formed integral with the base, said flanges and walls all extending in the same direction away from said base and the latter having through openings therein, mechanism mounted in said openings and being disposed between said flanges and walls, an outer plate secured to each of said end walls and covering the mechanism supporting openings therein, a cover applicable to said frame over the edges of said end walls and between said outer plates and having side portions cooperable with the inner surfaces of said flanges, a sealing strip secured within each end of said cover and being compressible against the entire edge of the adjacent end wall when said cover is applied to said frame, and a sealing strip secured to said base in contact with the inner side of each of said flanges and extend-

ing from one of said plates to the other, all of
said strips being inter-engageable to provide an
uninterrupted seal and said cover side portions
being formed to compress said base supported
5 sealing strips when said cover is applied to said
frame to enclose said mechanism.

3. A housing for switch mechanism or the like,
comprising, a frame having a base and side
flanges and end walls formed integral with the
10 base, said flanges and walls all extending in the
same direction away from said base and the lat-
ter being disposed between the former and having
aligned through openings therein, mechanism
15 mounted in said openings and being disposed be-
tween said flanges and walls, an outer plate se-
cured to each of said end walls and covering the
mechanism supporting openings therein and pro-
jecting outwardly beyond the edges of the ad-
joining wall, a cover applicable to said frame over

the edges of said end walls and between said out-
er plates and having resilient opposite side por-
tions biased outwardly for snug coaction with the
internal surfaces of said flanges, a sealing strip
secured within each end of said cover and being
engageable with the adjacent outer plate and
compressible against the entire edge of the adja-
cent end wall when said cover is applied to said
frame, and a sealing strip secured to said base in
contact with the inner side of each of said flanges
10 and extending from one of said plates to the
other, all of said strips being inter-engageable to
provide an uninterrupted seal and said cover side
portions being formed to compress said base sup-
ported sealing strip when said cover is applied to 15
said frame to enclose said mechanism.
